UNITED STATES PATENT OFFICE.

JULIUS O. GLASS, OF EAST ST. LOUIS, ILLINOIS.

OIL-CUP.

1,121,918.

Specification of Letters Patent. Patented Dec. 22, 1914.

Application filed February 24, 1914. Serial No. 820,438.

To all whom it may concern:

Be it known that I, JULIUS O. GLASS, a citizen of the United States, and resident of East St. Louis, Illinois, have invented certain new and useful Improvements in Oil-Cups, of which the following is a specification.

This invention relates to improvements in oil cups, and has for its object a cup provided with a sliding cover, and means for holding said cover in rigid position, and to prevent the same from becoming detached by movement of the machinery, to which the cup is applied.

A further object of my invention is to provide an oil cup with a disk-like cover supported by a spring mechanism whose tension can be adjusted so as to make an absolute leak-proof connection, the said spring mechanism also acting as a locking device to hold said cover in position.

Figure 1 is a perspective view of my complete invention. Fig. 2 is a side view of the cup showing a portion thereof in section, and my invention in position. Fig. 3 is a top plan view.

Referring to the drawings in detail 4 indicates an ordinary oil cup, which is provided with a screw-seated base 5, by which said cup is firmly held in position to that portion of the machinery to which it is applied. The said cup is provided with an ear or projection 6 having an internally screw-threaded bore 7, and on the opposite side of said cup is also provided an integral latch member 8 having a central depression or recess 9, and two angular or slanted side walls 10.

On the top of the oil cup 4 is located a disk 11, which forms a part of my improvement; this disk is provided with a central boss 12 and a projecting pin 13. Over this pin and resting upon the boss is placed a spring supporting member 14, which has a central opening 15 through which the pin 13 projects and through said pin immediately above the member 14 is placed a cotter pin 16; the spring supporting member 14 extends across the entire disk, one of its ends being bent in the form of a loop 17, which is provided with an aperture 18 on its upper portion and an aperture 19 on the

bottom portion, and through which a screw or bolt 20 is passed, the threaded portion of said bolt is screw-seated into an internally 55 screw-threaded bore 7 of the projection 6, and by means of said screw or bolt, the pressure or spring adjustment can be regulated by tightening or loosening said screw. The opposite end of the spring member 14 is bent 60 at the point indicated by the numeral 21, and extended downwardly, its free end 22 projecting slightly outwardly acting as a handle or hand-hold by which the spring can be bent outwardly to remove the same 65 from the latch member 8, but said spring member is so arranged and so tempered as to normally seat itself in the cavity of the latch member so as to hold the disk 11 in closed position over the top of the oil cup 70 proper, and by the tension of the spring member the contacting surface of the cup and disk provides a perfect joint. By this arrangement, when it is desired to fill the cup with oil or grease, all that is necessary 75 for the operator to do is to manipulate the spring, pulling the same outwardly from the cavity of the latch member and shifting the same to one side on its pivot, which is the screw or bolt 20, and after the cup has been 80 filled the operator merely returns the disk back to its position and the spring will automatically close itself by riding upon the inclined surface 10 of the latch permitting 85 the spring to seat itself in the cavity thereby placing and holding the disk or cap in perfect connection with the cup.

Having fully described my invention what I claim is:

1. A device of the class described comprising an oil cup, a disk cover located thereon, a spring member attached to the cover, its one end pivoted to the cup, and its other end held in a catch, substantially as specified.

2. A device of the class described comprising an oil cup, a cover, a pin secured to said cover, a spring member attached to said pin, one end of said spring member being looped and pivotally supported to the cup, 100 the other end bent in the form of a locking member and a catch for supporting the same.

3. A device of the class described com-

prising an oil cup provided with a smooth disk-like cover, a spring member supporting the cover and pivotally attached to the cup, and a locking means for supporting the spring member to retain the disk in proper position on the cup.

In testimony whereof, I have signed my

name to this specification, in presence of two subscribing witnesses.

JULIUS O. GLASS.
